Primary Examiner — Wendy L Arminio(74) *Attorney, Agent, or Firm* — Kimberly-Clark Worldwide, Inc.(57) **CLAIM**

We claim the ornamental design for a tissue product with embossing pattern, as shown and described.

DESCRIPTION

FIG. 1 is a front view of a tissue product with embossing pattern showing our new design;

FIG. 2 is a rear view thereof;

FIG. 3 is a right side view thereof;

FIG. 4 is a left side view thereof;

FIG. 5 is a top plan side view thereof;

FIG. 6 is a bottom plan side view thereof;

FIG. 7 is a reference view of FIG. 1; and,

FIG. 8 is an enlarged detail view of area 8 circumscribed within FIG. 7 oriented in perspective.

The dash-dot-dash broken lines surrounding the front of the tissue product with embossing pattern shown in FIGS. 1 and 7 depict the boundaries of the claim and form no part thereof. Behind the front surface, all dash-dash broken lines and areas including the thickness and rear of the article depict portions of the tissue product with embossing pattern that form no part of the claimed design. The dash-dot-dot-dash broken lines circumscribing the area of the detail in FIGS. 7 and 8 denote the boundaries of the detail and form no part of the claimed design.
